Sidney Sanders

United States Patent Office.

JOHN WILCOX, OF SPRINGFIELD, MASSACHUSETTS.

Letters Patent No. 73,272, dated January 14, 1868.

IMPROVED MACHINE FOR FILLING PAINT-CANS.

The Schedule referred to in these Letters Patent and making part of the same.

TO ALL WHOM IT MAY CONCERN:

Be it known that I, JOHN WILCOX, of Springfield, in the county of Hampden, and State of Massachusetts, have made and invented certain new and useful Improvements in Machines for Filling Paint-Cans, and other similar purposes; and I do hereby declare that the following is a full, clear, and exact description of the construction and operation of the same, reference being had to the annexed drawings, making a part of this specification, in which—

Figure 1 is a perspective view.

Figure 2 a sectional view of the filling apparatus, and

Figure 3 a perspective view of the adjustable collar and flange.

My invention relates to an improved machine for filling ground paints, or other substances of similar consistency, into cans or vessels, and is designed to facilitate such operations, by putting a specific and ascertained quantity into each can or vessel, without any weighing or measuring other than that performed by the machine itself, after once being properly adjusted to any given substance and quantity.

The nature of my invention consists in providing the central shaft, to which the stirrer is attached, with one, two, or more movable collars, such collars being further provided with an adjustable ring, which may be set at any desirable angle of inclination, according to the consistency of the substance to be impelled thereby; and further, in providing, in connection with the tunnel, a revolving cylinder and an accompanying plunger, so arranged that, on the withdrawal of the plunger, the paint or other substance in the tunnel is forced, by atmospheric pressure, into the cylinder, when, by a semi-revolution thereof, and a return stroke of the plunger, the paint or other substance is ejected from the nozzle into the can or vessel.

And, in carrying my invention into practical operation, I construct a strong frame, A, covered by a table or rest, B, through which is a large circular hole, wherein I set the tunnel C or other suitable receptacle for the paint. To the tube a, of the tunnel C, I attach, by brazing or other suitable means, a ring or collar, b, and on to the ring b, which is provided with a thread, I screw the angle-box D, which box I construct with both a vertical and a horizontal opening, the vertical opening being of about the same size as the tube a, while the horizontal opening, which is round, I make somewhat larger, or of sufficient diameter to allow the insertion and easy revolution of the cylinder E; and in two sides of the angle-box, or around each end of the horizontal opening therein, I form a recess, in each of which I place a packing, c c', of leather or other suitable material. To the bottom of the angle-box, or into the vertical opening thereof, I screw the nozzle d, which I further extend by means of a small pipe, d'.

I make the cylinder E from ten to twenty inches long, and from three to six inches, more or less, in diameter. One end thereof I construct smaller than the other, thus forming a shoulder about midway, the small end being closed while the large end is left open, as seen in fig. 3. On one side of the small end of the cylinder I make a circular aperture of about the same size as the tube a, and then, placing the packings c c' in the recesses provided therefor, and passing the small end of the cylinder through the horizontal opening of the angle-box, till the shoulder on such cylinder rests against the packing c, I thus secure it by means of the nut e and check-nut e', so arranging the nut e and check-nut e' as to form, in combination with the packing c', a practically tight joint without materially impeding the revolution of the cylinder E, which is operated by means of the handle F, attached thereto, as seen in fig. 1.

And further, I construct a rest, G, in which I make a slot or opening, f, running lengthwise thereof, one end of which rest I attach to the angle-box D, while the other end is supported by a cross-bar or stretcher, in the frame A, as seen in fig. 1.

The outer end of the rest, G, I provide with a perforated elevation, g, for the support and guidance of the plunger-rod h, and to one end of the rod h, I attach the plunger H, which I construct of such a size as to fill the interior of the larger part of the cylinder E, or as nearly so as may be, and still allow the plunger a free and ready stroke.

And further, I construct or provide the rod h with a pin or projection, s, on the lower side thereof, and extending downwards into the slot f, wherein it moves. I also provide stops i i', which I arrange and secure, by means of set-screws, at any desired point along the slot f.

For the purpose of operating the plunger, I provide and attach, to one side of the rod *h*, a straight gear, *k*. I also provide a wheel, *m*, meshing into the gear *k*, such wheel turning on a pivot in the rest *G*, and being moved by means of the handle *H'*, provided for that purpose.

I also provide a central shaft, *J*, which rests in the step *n*, and is operated by the bevel-gear *L*, and to the side of the shaft *J*, I attach an ordinary stirrer, *o*.

I also provide one, two, or more collars, *M*, fig. 2, which I place around the shaft *J*, near the lower end thereof, securing them at any desirable point by means of a set-screw, *P*, and I provide and attach to one side of such collars what I term an adjustable wing, *q*, which may be arranged at any desired angle of inclination, and thus secured by means of the nut *r*.

My improved machine being thus constructed and arranged, it will be seen that it depends principally on atmospheric pressure for the drawing and measuring of the paints or other substances. All joints, therefore, around the measuring-apparatus must be practically air-tight, and if not so at the commencement of operations, they will soon become so by the action of the paints or other similar substances, which act both as a packing and a lubricator.

The machine is set in motion by belting on to the pulleys *N N'*, the former of which is loose and the latter fast on its arbor, and paint being put in the tunnel, it is kept in motion by the stirrer, whereby it is warmed and made thinner, while the adjustable wings tend to work it downward towards the cylinder, and in filling cans, the operator, by means of the handle *F*, has only to turn the cylinder till the aperture on the side thereof communicates with the tunnel, when, by a backward stroke of the plunger, the cylinder is filled; then, turning the cylinder half way over, or till it communicates with the nozzle, and, by a reverse or forward stroke of the plunger, the paint is ejected into the can or other vessel.

The length of the stroke, and, at the same time, the heft of the charge, are regulated and determined by means of the stops across the slot in the rest, in conjunction with the pin or projection on the plunger-rod. The stops may be set at any required distance within the limits of a given machine, according to the heft and consistency of the substance in the tunnel. The length of the stroke necessary to put a specific quantity of any given material in a can must be determined at first by experiment. I find, from experience, that my machine works better when the plunger is not driven in till stopped by the shoulder in the cylinder. It should, therefore, be brought to rest a little before reaching that point.

I construct the frame of my machine of wood, the rest of iron, except the packings, which I make of leather. The dimensions may be varied according to circumstances.

Having thus described my improvement, and how the same is to be constructed, what I claim as my invention, and for which I wish to secure Letters Patent of the United States, is—

1. I claim the adjustable wing *q*, when constructed and arranged substantially as described, and for the purpose specified.
2. I claim the movable collar *M*, in combination with the wing *q*, shaft *J*, and tube *a*, substantially as described, and for the purpose specified.
3. I claim the angle-box *D*, when recessed, as described, in combination with the tube *a* and cylinder *E*, substantially as described, and for the purpose set forth.
4. I claim the cylinder *E*, when constructed with a shoulder and side aperture, as described, in combination with the angle-box *D*, packings *c c'*, nut *e*, and check-nut *e'*, substantially as specified, and for the purpose set forth.
5. I claim the packings *c c'*, when constructed and arranged in the manner described, and for the purpose specified.
6. I claim the rest *G*, constructed and arranged as described, and for the purpose set forth.
7. I claim the stops *i i'*, in combination with the slotted rest *G*, rod *h*, and pin *s*, as and for the purpose specified.
8. I claim the rod *h*, when provided with a pin, *s*, in combination with the rest *G*, plunger *H*, and cylinder *E*, substantially as described, and for the purpose specified.

JOHN WILCOX.
